J. P. SMALL.
CORN SHELLER.

Patented July 21, 1835.

8986X

July 21, 1835

8986 X John. P. Howell of Belvoirton New Hampshire
Letters Patent.

The Petitioner requests to have his Letters Patent and specification of the invention
containing a description and the mode of the said John P. Howell himself,
of his improvement in a machine for threshing grain.

To all to whom these Presents shall come... Be it known that I John
Howell of Belvoirton in the County of Belknap and State of New
Hampshire have invented a new and useful machine for threshing grain
which I am in the act of separating it from the cob and the chaff, and that
the following is a full and exact description thereof. The frame of the
machine is a box 8 feet 3 inches long 16 inches wide, and 10 inches
deep, the bottom slanting forward and furnished at the fore end with
a slide through which the corn is received after being separated from the
cob and chaff. Immediately above the bottom the after end of the box
open in order to suffer the chaff to be removed out. A block of wood
is in form a truncated cone, but so slightly conical that for brevity sake
it may be termed a cylinder, is suspended by the rear, upon the sides
of the box as near as possible to the after end. It is diameter, about 11
inches, and its length such as to occupy the entire space between the
end of the box. It is furnished with eight rows of small square flat
headed bolts, running the length spirally, and vertices within a shell
placed beneath it in the box, of equal length corresponding with the shape
and embracing about one half of its circumference. This shell is likewise
furnished with rows of teeth running spirally but in a direction so as
to enter into the cylinder. It rests on two coil springs, affixed one upon
each side of the box, by means of which it is pressed upward to the cylinder
so as to yield to accommodate the size of the cob of corn and
the cob which are to pass between it and the cylinder. Over the cylinder
is a cap fastened to the box by bolts and staples, neither so tight nor
so fast as to prevent the cylinder from turning between it and the shell.
The corn and cob is passed by this machine, the former dropping down

through holes at the transom part of the shell, the latter being connected around by the motion of the cylinder and the main bulk between the after edge of the shell and of the cap which is made sharp to and then passed out and fastened with iron. This opening is protected by leather to prevent the escape of the mercury from. In the forward and upper part of the box is a chamber containing a revolving fan set in motion by a band from a wheel on the side of the cylinder. The chamber opens immediately under the holes in the shell through which the current passes and then the draft is blown off through the opening before mentioned in the after end of the box. The whole motion is produced by a crank affixed to the side of the cylinder. The box is suspended by legs of iron ^{long} about 6 feet in my workshop and not before known in the above described machine. The combination or manner in which I have put together the several parts in the manner above described is in testimony that the same is a full and exact description of the construction and mode of operation of my machine as invented or improved by me. I have hereunto set my hand this twelfth day of June eighteen hundred and thirty five.

Age.
